DESIGN FOR A GREASE FITTING CAP

Lionel H. Rosenthal, Milwaukie, Oreg.

Application May 14, 1948, Serial No. 146,359

Term of patent 14 years

(CL. D14—6)

To all whom it may concern:

Be it known that I, Lionel H. Rosenthal, a citizen of the United States, residing at Milwaukie, in the county of Clackamas and State of Oregon, have invented a new, original, and ornamental Design for Grease Fitting Cap, of which the following is a specification, reference being had to the accompanying drawings, forming a part thereof.

In the drawings:

Fig. 1 is a perspective side view of the grease fitting cap, showing my new design;

Fig. 2 is a top plan view of the same; and

Fig. 3 is a side elevation of the same.

I claim:

The ornamental design for a grease fitting cap, as shown.

LIONEL H. ROSENTHAL.
